UNITED STATES PATENT OFFICE.

GEORGE A. MARTIN, OF CHICAGO, ILLINOIS.

WINDOW FRAME AND SASH STRUCTURE.

1,397,221.

Specification of Letters Patent.

Patented Nov. 15, 1921.

Application filed October 25, 1920. Serial No. 419,250.

To all whom it may concern:

Be it known that I, GEORGE A. MARTIN, a citizen of the United States, and a resident of Chicago, in the county of Cook and State 5 of Illinois, have invented certain new and useful Improvements in a Window Frame and Sash Structure, of which the following is a specification.

This invention relates to improvements in 10 window frames and sashes of the type in which the sashes are counterbalanced by weights attached thereto by flexible connections, such as cords or chains, which weights operate in vertical passages or pockets located in the sides of the frames outwardly 15 of vertical guideways therein for the sashes, and it consists in certain peculiarities of the construction, novel arrangement, combination and operation of the various parts 20 thereof as will be hereinafter more fully set forth and specifically claimed.

In window frames and sashes of the above mentioned type heretofore in general use, it has been a difficult task to reattach the 25 weights for the sashes to the suspending devices therefor, when said weights have become accidentally detached by the breakage of the cords or chains, and it has also been difficult to adjust the cords or chains after 30 they have become stretched or elongated. In order to remove, change, reattach, or to adjust the suspending devices of the weights in the old style window frames and sashes, it has been usually necessary to remove the 35 molding or beading on the inner surfaces of the window frames and then to remove the sashes from the frames, which operation requires considerable time and labor, and besides, causes dust and dirt collected on the 40 window frames and sashes and within the dirt boxes of the former to be scattered or distributed in the room, as is well known to those skilled in the art to which my invention pertains.

45 To provide a window frame and sash structure of such construction, combination and operation of its parts as to enable ready access to the passageway or pockets of the frames in order to attach weights to the 50 cords or chains of the sashes or to adjust said suspending devices without the necessity of removing the sashes from the frame is the principal object of my invention.

Other objects and advantages of the invention will be disclosed in the following 55 description and explanation.

In the accompanying drawing which serves to illustrate an embodiment of the invention—

Figure 1 is an inner face view of a portion 60 of a window frame and sash structure embodying my improvements showing the sashes thereof in their normal positions.

Fig. 2 is a vertical sectional view of like parts showing them in the same positions 65 as shown in Fig. 1 but illustrating my new or improved construction of the parts of the window frame, sashes and weight connecting devices.

Fig. 3 is a greatly enlarged fragmental 70 view of one of the upper corners of one of the sashes showing the means for detachably connecting the chain of one of the weights thereto, and

Fig. 4 is a plan sectional view taken on 75 line 4—4 of Fig. 2 looking in the direction indicated by the arrows.

Like numerals of reference refer to corresponding parts throughout the different views of the drawing.

The reference numeral 7 designates a portion 80 of the wall of a building in which is located a window frame constructed according to my improvements, which frame is designated as a whole by the numeral 8 and 85 is rectangular in shape and of any suitable size and material. Each of the vertical sides or walls of the frame is provided with a vertically disposed pocket or passageway 9 which extends from the upper part of the 90 transverse portion of the frame to the corresponding portion at the lower part thereof as is clearly shown in Fig. 2 of the drawing. This pocket or passageway has horizontally 95 located in its lower portion at a suitable distance above the floor thereof a plate or block 10 which is perforated or provided with cut-out portions 11 see Figs. 2 and 4, to permit dirt and the like to pass into the compartment 12 or dirt box which is formed 100 by the horizontal partition or block 11 and the walls and bottom of the passageway or pocket.

The inner wall 13 of each of said pockets, or the inner surface of each of the upright 105 side portions or jambs of the frame is pro-

vided with a parting strip 14 which is located midway between the edges of said wall 13 and together with the inner edge of the outer wall 15 of said pocket or frame and a 5 vertical bead or cleat 16 secured to the inner edge of the inner face wall 17 of the pocket or jamb provides guideways for the upper and lower sashes which are designated as a whole by the reference numerals 18 and 19 10 respectively. The inner wall 13 of each of the pockets or passageways 9 is provided in its upper portion with a doorway 18^a which is vertically disposed and extends upwardly from a point at about the horizontal middle 15 of the upper rail of the lower sash and the lower rail of the upper sash when said sashes are in their normal or closed positions to a point near the upper end of the wall 13 as shown in Fig. 2 of the drawings. This 20 doorway 18^a is closed by means of a door 19^a which is rabbeted at its upper and lower ends to fit correspondingly shaped rabbets in the upper and lower ends of the doorway. The door 19^a has on its surface adjacent the 25 side rails of the sashes a parting strip 20 which coincides vertically with the parting strip 14 on the fixed wall 13 of each of the side portions of the frame.

Near its upper end each of the walls 13 is 30 provided on each side of the parting strip 14 with a cut-away portion 21 in each of which is journaled a pulley 22, over which pulleys are passed chains or cords 23 and 24 to the end of each of which and located in the 35 pocket 9 is attached a weight 25 of the ordinary or any preferred construction. Each of the upper corners of each of the sashes is provided with a downwardly inclined and elongated opening or mortise 26, see Fig. 40 3 of the drawing, which mortise is formed in the vertical or side rails of the sashes as shown. The upper end of each of the side rails of each sash is provided with a transversely disposed recess or depression 27 45 which extends from the opening or mortise 26 inwardly to near the inner surface of said rail and terminates in a vertical opening 28.

This recess and opening in the upper end of each of the side rails of each sash is for 50 the reception of the upper portion of a fastening wire which is designated as a whole by the numeral 29 and comprises a main body portion 30 having a coil 31 and a loop 32 which are adapted to be located in the 55 elongated opening 26 of each of the side rails of each sash where it can be securely held in place by means of a screw 33 extended from the inner face of each of the side rails of each sash into the opening 26 thereof. The 60 fastening wire 29 also comprises a horizontally disposed portion or arm 34 which is designed to rest in the groove or depression 27 and which terminates in a downwardly extended arm 35 which engages the opening 28

in the upper end of each of the side rails of 65 each sash.

From the foregoing and by reference to the drawing, it will be readily understood and clearly seen that, assuming the inner end of each of the cords or chains 23 and 24 70 is connected to a loop of one of the fasteners 29 and that said fasteners are located and held in the position shown in Fig. 3 of the drawing by the means above stated, and it is desired to obtain access to the pockets or 75 passageways 9 for adjusting the weights on the cords or chains or for detaching said weights from the cords in order to replace them with others, all that is necessary to be done is to lower the uppermost sash to its 80 downward limit, when it is apparent that the door 19^a of the doorway 18^a can be readily removed so that access may be had to the pockets 9 for removing the detached weight therefrom and for adjusting the 85 weights on the cords or for performing any other act which may be necessary in connection with the cords and weights, after which it is obvious that the door 19^a may be placed in the doorway so as to close the same, when 90 it is apparent the sashes may be moved up and down as desired.

By providing each of the fasteners 29 with the arm 27, it is apparent that said arm will provide means by which the fastener 95 can be removed from the opening 26 after the screw 33 which holds it in place is removed.

Having thus fully described my invention, what I claim as new and desire to secure by Letters Patent is—

1. The combination with an upright rectangular frame having a vertically disposed passageway or pocket, the outer surface of the inner wall of said pocket having a vertical guideway and being provided in its upper portion with a removable door and above said door with an opening, of a sash located in said guideway for vertical movement therein, a pulley journaled in said opening, said sash having in the upper portion of one of its side rails a downwardly extended opening and in the top of its said rail a transversely extended depression terminating in a vertical opening, a fastener located in said downwardly extended opening and comprising a body portion having a coil and a loop and a horizontally disposed arm terminating in a vertically disposed arm to engage said depression and vertically disposed opening respectively, a flexible connection extended over said pulley and detachably fastened at one of its ends to said fastener, a weight on the other end of said flexible connection, and a screw extended in to the upper portion of one of the side rails of said sash to engage the loop of said fastener.

2. As an improved article of manufacture,

a window sash comprising a rectangular frame having in the upper portion of one of its side rails a downwardly extended opening and in the top of said side rail a transversely extended depression terminating in a vertical opening, a fastener located in said downwardly extended opening and comprising a body portion having a coil and a loop and a horizontally disposed arm terminating in a vertically disposed arm to engage 10 said depression and vertically disposed opening respectively, and a screw extended into the upper portion of the said side rail of the sash to engage the loop of said fastener.

GEORGE A. MARTIN.
